MULTIPLE FUSE PLUG

William Skojec, Binghamton, N. Y., assignor of one-twelfth to Paul Skojec, Sr., and five-twelfths to Andrew Stroka, both of Binghamton, N. Y.

Application February 28, 1938, Serial No. 193,138

2 Claims. (Cl. 200—125)

- This invention relates to multiple fuse plugs for insertion in the ordinary house lighting or other electric circuits.
- An object of the invention is to provide a fuse plug having a plurality of fuses adapted to be individually and successively brought into the circuit whereby the fuse plug need not be discarded upon the blowing of a fuse but may be used repeatedly until the fuses are all exhausted.
- 10 A further object is to provide a multiple fuse plug in which the fuse magazine is rotatably mounted exteriorly of the body of the fuse plug so as to be easily inspected and manipulated by persons unskilled in the electrical art.
- 15 A further object is to provide a multiple fuse plug which may be formed of a few strong simple and durable parts, which will be inexpensive to manufacture, and which will not easily get out of order.
- 20 With the above and other objects in view the invention consists of certain novel details of construction and combinations of parts hereinafter fully described and claimed, it being understood that various modifications may be resorted to
- 25 within the scope of the appended claims without departing from the spirit or sacrificing any of the advantages of the invention.

In the accompanying drawing forming part of this specification,

- 30 Figure 1 is a side elevation of a multiple fuse plug constructed in accordance with the invention and showing two fuse magazines applied to the body of the plug.
- Figure 2 is an end elevation of the fuse plug shown in Figure 1 and showing one of the fuse magazines in front elevation.

Figure 3 is an enlarged cross sectional view taken on the line 3—3 of Figure 2 and showing the electrical connections of the fuses and showing the stub shafts upon which the magazines are rotatably mounted.

Figure 4 is a rear elevation of one of the fuse magazines showing the arrangement of the fuses therein.

45 Figure 5 is a rear elevation of a modified form of the invention.

Referring now to the drawing in which like characters of reference designate similar parts in the various views, 10 designates the body of the plug the same being provided with conventional prongs 11 and spring contacts 12 which are insulated from each other by insulating washers 13 and insulating tubes 14, the latter forming supports for mounting studs 15 on the sides of the

body member, which studs form stub shafts for rotatably mounting the fuse magazines 16.

Contact screws 17 are connected to the prongs and contact screws 18 are connected to the spring contacts, the heads of these screws being located outside of and at opposite sides of the body member 10. The heads of the screws 17 and 18 of a prong and respective spring contact 12 on the same side of the body member 10, form means for connecting fuses in series circuit with the 10 prong and the spring.

Rotatably mounted on each stub shaft 15 is a respective fuse magazine 16, the magazine being formed of insulating material, there being a disc having a recess 19 formed on the outer face and communicating with a plurality of circuitous grooves 20. Each groove receives a respective fuse 21 and the opposite ends of the fuse are exposed through openings 22 formed at the ends of the respective groove. Enlarged contact heads 23 are formed on the exposed ends of the fuse for engagement with the heads of the contact screws 17 and 18.

Springs 24 and 25 are mounted in respective circumferential grooves on each stub shaft 15. 25 The spring 24 is sprung into a groove 26 in the axial opening of the magazine while the spring 25 is disposed between the magazine and the side face of the body member 10. These springs rotatably mount the magazine so that the fuses 30 may be successively moved into engagement with the heads of the contact screws as each fuse burns out.

A modified form of the invention is shown in Figure 5 in which a single fuse 27 is mounted in 35 a magazine 28 which is formed of a bar of insulating material and is provided with a central opening 29 to receive one of the stub shafts 15 and is also provided with a spring ring 30 to rotatably hold the magazine on the shaft. The 40 magazines of the type shown in Figure 5 are designed for use as a spare to replace a multiple fuse magazine when multiple fuse magazines are not available.

In the preferred embodiment of the magazine 45 the recess 19 is closed by a transparent pane 31 which is held in place by a split ring clamp 32 engaged in a groove 33 formed in the wall of the recess.

From the above description it is thought that 50 the construction and operation of the invention will be fully understood without further explanation.

What is claimed is:

1. A multiple fuse plug comprising a plug body, 55

- prongs and spring contacts in the body forming circuit terminals, means insulating a prong and a respective spring contact from each other, contact screws connected to the prongs, contact screws connected to the spring contacts, all of the screws having heads located outwardly of and at opposite sides of the plug body, fuse magazines rotatably mounted on said sides of the body, a plurality of fuses arranged in a circuitous manner in each magazine and each terminating exteriorly of the magazine in contact ends adapted to bridge the contact screw of one of the prongs and its associated spring contact for connecting the prong and the spring in series circuit, and studs projecting from the sides of the plug body upon which said magazines are rotatably mounted, rotation of the magazines on the studs advancing the fuses successively into circuit closing position when a fuse burns out.
2. A multiple fuse plug comprising a plug body, prongs and spring contacts in the body forming circuit terminals, means insulating a prong and a respective spring contact from each other, con-

tact screws connected to the prongs, contact screws connected to the spring contacts, all of the screws having heads located outwardly of and at opposite sides of the plug body, fuse magazines rotatably mounted upon said sides of the body, a plurality of fuses arranged in a circuitous manner in each magazine and each terminating exteriorly of the magazine in contact ends adapted to bridge the contact screw of one of the prongs and its associated spring contact connecting the prong and the spring in series circuit, studs projecting from the sides of the plug body upon which said magazines are rotatably mounted, rotation of the magazines on the studs advancing the fuses successively into circuit closing position when a fuse burns out, and split ring springs on the studs engaging the magazines for properly positioning the magazines for rotatably mounting the magazines at a predetermined distance from the fuse plug body to assure good electrical contact of the fuses with the contact screws.

WILLIAM SKOJEC.
